UNITED STATES PATENT OFFICE

WILLIAM J. WISWALL, OF PORTLAND, OREGON, ASSIGNOR TO AMERICAN SALES BOOK COMPANY, LIMITED, OF TORONTO, CANADA, A CORPORATION OF CANADA

ALIGNING DEVICE FOR MAKING MANIFOLD RECORDS

Application filed January 11, 1928. Serial No. 245,845.

This invention relates to apparatus for aligning record strips, and with respect to its more specific features, to a small, portable apparatus wherewith a plurality of superposed paper record strips, adapted for autographic manifold inscription, may be efficiently aligned.

One of the objects of the invention is the provision of a simple apparatus adapted to accommodate a number of strips, and providing for rapid and convenient changing of the number of strips which may be utilized.

Another object of the invention is the provision of a practical apparatus whereby each record strip is controlled by its individual aligning pin, the apparatus being compact, convenient and readily portable.

Other objects of the invention will be in part obvious and will in part appear herein-after.

The invention accordingly comprises the features of construction, combinations of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the accompanying drawing, in which:

Fig. 1 is a plan of the apparatus showing it in open condition ready for use;

Fig. 2 is a side elevation of the apparatus;

Fig. 3 is an enlarged longitudinal, vertical section through a portion of the apparatus, showing the pin aligners in their aligning positions;

Fig. 4 shows a portion of the aligning apparatus in general side elevation, the aligning pins being out of aperture engagement with the record strips;

Fig. 5 is a plan view of a portion of one of the carriers or plates, partly in section.

Referring now more specifically to the drawings, the numeral 1 indicates a writing base, platen, or table, to which is connected a container part 2, the bottom 3 of the container part being a continuation of the base 1 through a broad hinge 4. One end of the con-

tainer 2 has an end 5 and two side walls 6 and 7 having the overhanging flange 8, the walls 6 and 7 being of reduced height at 9, the ends of the walls 9 being connected by a wall 10, the supply of record strips being adapted to be disposed in the container between the walls 5, 6, 7 and 10.

Any practical number of record strips may be employed, three being illustrated. The record strips are indicated by the numerals 11 and each has a series of printed forms, as for instance bill heads, and each strip also has a series of aligning apertures 12, the apertures intervening the printed forms. When the several strips are in superposed relation with the printed forms in registry with each other depthwise, the set of aligning apertures adjacent the registering printed forms are also in registry with each other, the result being that by aligning the apertures with each

other, registration of the printed forms is effected. Between succeeding printed forms the record strips have transverse weakening lines as at 13, and the superposed strips are folded zigzag to form a flat packet of record strips for convenient reception in the container, as for instance illustrated in Fig. 2.

Upstanding at opposite sides from the base 1 are the rigid gage abutments 14 and 15 which are of suitable stiff material as metal, the record strips 11 being adapted to pass between these abutments, the faces of the abutments being smooth on the side facing the container.

Also at the opposite sides of the base 1 are the upstanding guides 16 and 17 which may be plates extending at angles from the abutments 14 and 15, and the ends of the guides 16 and 17 may be bent into parallel relation with the abutments 14 and 15, as indicated at 18 and 19. Fixed to the upper ends of the members 15, 17 and 19 is a plate 20. Overhanging the upper ends of the members 14 and 16 is a keeper plate 21 pivoted at 22 on a pin upstanding from a bracket 23 fastened to the inside of the guide 16. The plate 21 has a notch 24 to permit the play of an actuator arm 25 hereinafter described.

At the end of the base 1 remote from the container, a strip clamp jaw 26 is pivoted

at opposite sides of the base as at 27, and the front edge of the jaw 26 is adapted to serve as a tear-off bar for the strips.

Lying between the guides 16 and 17 and at one side of the upstanding abutments 14 and 15, are a plurality of relatively superposed plates, or carrier plates, all of which are alike and are generally indicated by the numerals 26. These plates are preferably made of thin sheet metal and the upper and lower surfaces thereof are broad and smooth so as to be adapted to rest uniformly upon the record strips 11. The respective plates 26 are freely movable up and down in the apparatus between the guides 16 and 17 and are adapted to have swinging movement on the abutments 14 and 15. Each of the plates 26 has a strip aligning pin 27 projecting from one face, the lower face in the embodiment illustrated, the outer end of the pin upwardly inclining in a forward direction as indicated at 29; that is, in the direction of advance away from the container 2. In each of the plates 26 is a recess 28 directly opposite the pin on that plate, the recess 28 being of a size or diameter to receive the end of the pin on the next adjacent upper plate 26.

In the embodiment illustrated the plates 26 are formed from a folded plate or sheet of strip material bent at 29 to form two plies 30 and 31, these plies lying opposite each other, the pin 27 being struck down from the lower ply and the recess 28 being provided in the upper ply. Each carrier plate is provided with a thin, resilient metal clamping jaw 32 pivoted thereto at 33 for movement in and out between the forward ends of the plies 30 and 31. Held to each plate 26 by its clamping jaw 32 is a transfer sheet 34, which extends forwardly over the writing table 1 in manifolding relation with the superposed record strips. As the clamping jaw 32 and the carrier plates 26 are of resilient metal, the transfer sheets are efficiently held and may readily be removed and replaced. The transfer sheets may be the customary "carbons" used for manifolding inscription.

Each carrier plate 26 has a rearwardly extending stripper which is adapted to cooperate to strip the record strips from the aligning pin 27 thereon. In the embodiment illustrated, this stripper comprises a stiff bow or yoke, the opposite arms of which are loosely articulated with the carrier plates 26 as by being pivoted thereto at 35. The cross piece 36 of the bow lies across the face of the adjacent record strip, and the arms 37 lie beneath the plate 26, the pivotal point 35 being somewhat within the edge 29 of the plate 26, so that the arms 37 may contact with the under face of the plate 26 to limit the relative movement between the plate and the bow in an upward direction. The strippers are also utilized to effect upwardly shifting movement of the plates 26 around the abut-

ments 14 and 15, and to this end the arms 37 should be quite stiff to serve as thrust transmitting rods.

The actuator arm 25 is pivoted to the base 1 at 39, Fig. 3, and is pivotally urged away from the abutments 14 and 15 by the spring 40. The arm 25 has a finger piece 41 for conveniently actuating it to shift the carrier plates 26, and the upper end of the actuator arm 25 is adapted to play in the slot 24 of the keeper 21, when said keeper is in position overlying the abutment 14 and the guide 21. At this point it may be mentioned that the keeper 21 is movable on its pivot 22 out of position overlying the abutment 14 and the guide 21, thereby providing convenient access to the space between the guides 21 and 17 for the insertion and removal of the carrier plates 26.

Along the forward edge of the actuator arm 25 is an upwardly extending series of teeth or cams, the teeth being spaced a greater distance from each other as their height on the arm from the pivotal point 29 increases. When the carrier plates are in aligning position, as illustrated for instance in Fig. 3, the cross piece 36 of the strippers lie immediately above one another in the path of the actuator arm 25. As the arm 25 is manually urged forwardly by the operator, first the lower stripper contacts the actuator arm and then the next upper stripper, and so on. Forward movement of the actuator arm thrusts the stripper arms 37 forwardly and causes the carrier plates to swing or shift upwardly and in an arcuate path on the abutments 14 and 15, thereby disengaging the aligning pins 27 from the aligning apertures 12.

In operation, the keeper 21 will be shifted to the dotted line position shown in Fig. 1, whereupon the proper number of carrier plates may be introduced between the guides 16 and 17 so as to lie behind the abutments 14 and 15. Before inserting the carrier plates, the lowermost record strip will be drawn from the container so as to extend between the guides 16 and 17 and lie upon the writing table 1 and beneath the clamping jaw 26. Thereupon, a carrier plate will be introduced and permitted to rest upon the record strip. Then another record strip is drawn from the container in the manner explained and will lie upon the carrier plate which has been inserted. Thereupon another carrier plate will be inserted between the guides so as to rest upon the second record strip. Then another record strip and another carrier plate are set in place, and so on. The carrier plates lying intermediate the record strips will, of course, have transfer sheets, 34, extending therefrom over the writing table. Should the printed forms not be in registry, they may readily be registered by advancing the record strips, whereupon the

5 After inscription has been made, the actuator arm 25 may be urged forwardly whereupon the aligning pins will be disengaged from the aligning apertures in the record strips, permitting the record strips to be readily advanced to place new printed forms over the writing table, and to carry the inscribed forms past the clamping jaw 26, where they may be torn off at will. Before the new printed forms have been drawn to writing 10 position on the platen, the actuator will be released, whereupon the spring 40 will cause it to retract, thus allowing the carrier plates with their aligning pins to drop onto the respective record strips. Thereupon completion 15 of advance of the record strips will cause the apertures therein to be engaged by the aligning pins so that the printed forms about to be inscribed will be arrested above the writing table in proper position for inscription. 20

Thus by the above described construction are accomplished the objects hereinbefore referred to.

Since certain changes may be made in the 30 above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention 40 herein described, and all statements of the scope of the invention which, as a matter of language, might be said to fall therebetween.

Having described my invention, what I claim as new and desire to secure by Letters 45 Patent is:

1. A strip aligning apparatus including, in combination, a pair of upstanding abutments between which the strips pass, a plurality of upwardly shiftable plates in superposed relation to each other at one side of said abutments, said plates having projecting aligning pins, next adjacent of said plates having the one a recess for reception of the end of the aligning pin on the other, and a member manually movable to shift said plates upwardly.

2. A strip aligning apparatus including, in combination, a pair of upstanding abutments between which the strips pass, a plurality of upwardly shiftable plates in superposed relation to each other at one side of said abutments, said plates having projecting aligning pins, next adjacent of said plates having the one a recess for reception of the end of the aligning pin on the other, and a member

manually movable to shift said plates upwardly, said plates being unconnected one to another.

3. A strip aligning apparatus including, in combination, a pair of upstanding abutments 70 between which the strips pass, a plurality of upwardly shiftable plates in superposed relation to each other at one side of said abutments, said plates having projecting aligning pins, next adjacent of said plates having the one a recess for reception of the end of the aligning pin on the other, and a member manually movable to shift said plates upwardly, 75 said plates having rearwardly extending strippers loosely articulated thereto.

4. A strip aligning apparatus including, in combination, a pair of upstanding abutments between which the strips pass, a plurality of upwardly shiftable plates in superposed relation to each other at one side of said abutments, said plates having projecting aligning pins, next adjacent of said plates having the one a recess for reception of the end of the aligning pin on the other, and a member manually movable to shift said plates upwardly, 80 said plates having rearwardly extending strippers loosely articulated thereto and lying in the path of movement of said manually movable member.

5. A strip aligning apparatus including, in combination, a pair of upstanding abutments between which the strips pass, a plurality of upwardly shiftable plates in superposed relation to each other at one side of said abutments, said plates having projecting aligning pins, next adjacent of said plates having the one a recess for reception of the end of the aligning pin on the other, and a member manually movable to shift said plates upwardly, 95 said plates having rearwardly extending strippers loosely articulated thereto and lying in the path of movement of said manually movable member.

6. A strip aligning apparatus including, in combination, a pair of upstanding abutments between which the strips pass, a plurality of upwardly shiftable plates in superposed relation to each other at one side of said abutments, said plates having projecting aligning pins, next adjacent of said plates having the one a recess for reception of the end of the aligning pin on the other, and a member manually movable to shift said plates upwardly, 100 said plates having means for holding transfer sheets.

6. A strip aligning apparatus including, in combination, a pair of upstanding abutments between which the strips pass, a plurality of upwardly shiftable plates in superposed relation to each other at one side of said abutments, said plates having projecting aligning pins, next adjacent of said plates having the one a recess for reception of the end of the aligning pin on the other, and an oscillatable actuator having teeth, said plates having loosely articulated, thrust transmitting rods with which said teeth are adapted to contact, respectively, so as to swing said plates on said abutment in an upward direction.

7. A strip aligning apparatus including, in combination, a pair of upstanding abutments between which the strips pass, a plurality of upwardly shiftable plates in superposed relation to each other at one side of said abutments, said plates having projecting aligning pins, next adjacent of said plates having the one a recess for reception of the end of the aligning pin on the other, a manually oscillatable actuator arm, each of said 115 120 125 130

plates having a stiff bow pivoted thereto and in the path of movement of said arm.

8. An aligner of the character described including, in combination, a folded plate the plies of which are opposite each other, one of said folds having an aligning pin projecting therefrom, and the other having an aperture opposite said pin.

9. An aligner of the character described including, in combination, a folded plate the plies of which are opposite each other, one of said folds having an aligning pin projecting therefrom, and a stripper bar pivoted to said plate and having a part adapted to contact an under part of said plate, thereby to limit relative movement between said plate and bar in one direction.

10. An aligner of the character described including, in combination, a folded plate the plies of which are opposite each other, one of said folds having an aligning pin projecting therefrom, and the other having an aperture opposite said pin, and a stripper bar pivoted to said plate and having a part adapted to contact an under part of said plate, thereby to limit relative movement between said plate and bar in one direction.

11. An aligner of the character described including, in combination, a folded plate the plies of which are opposite each other, one of said folds having an aligning pin projecting therefrom, and the other having an aperture opposite said pin, a stripper bar pivoted to said plate and having a part adapted to contact an under part of said plate, thereby to limit relative movement between said plate and bar in one direction, and a clamp jaw pivoted to said aligner and movable into and out of clamping position between said plies.

12. A strip aligning apparatus including a carrier having an aligning pin projecting therefrom and a pin receiving recess in said carrier directly opposite said pin.

13. A strip aligning apparatus including, in combination, a pair of upstanding abutments between which the strips pass, a plurality of upwardly shiftable plates in superposed relation to each other at one side of said abutments, said plates having projecting aligning pins; next adjacent of said plates having the one a recess for reception of the end of the aligning pin on the other, a member manually movable to shift said plates upwardly, laterally disposed upstanding guides between which said plates lie, and a keeper overchanging said plates and pivotally movable out of keeping position.

In testimony whereof I affix my signature.

60 WILLIAM J. WISWALL.
